UNITED STATES PATENT OFFICE.

FRANK O. KING, OF GLENCOE, ILLINOIS.

DESIGN FOR A DOLL.

Application filed October 16, 1922. Serial No. 3,993. Term of patent 7 years.

To all whom it may concern:

Be it known that I, FRANK O. KING, a citizen of the United States, residing in the village of Glencoe, in the county of Cook and State of Illinois, have invented a new, original, and ornamental Design for a Doll, of which the following is a specification, reference being had to the accompanying drawings, forming part thereof, and in Figure 1, of which the doll is shown in face view, and in Figure 2, of which the doll is shown in rear view.

I claim:

The ornamental design for a doll substantially as shown.

FRANK O. KING.
